PORTABLE DIGITAL METER

William J. Smith, Littleton, Colo., assignor to Frost Engineering Development Corporation, Englewood, Colo., a corporation of Colorado

Filed June 13, 1963, Ser. No. 75,334

Term of patent 3½ years

(Cl. D26—1)

FIG. 1.

FIG. 2.

Des. 198,913

PAGE 2

FIG. 3.

FIG. 4.

FIG. 5.

FIG. 6.

FIGURE 1 is a front isometric view of the portable digital meter showing my new design with the hinged handle in retracted position;

FIGURE 2 is a side elevational view thereof, with the opposite side being identical;

FIGURE 3 is a bottom plan view thereof with the wire stand moved to the rear and folded against the back of the meter;

FIGURE 4 is an isometric view from the rear and right side with the wire stand as in FIGURE 3;

FIGURE 5 is a partial side elevational view on a reduced scale with the hinged handle in extended position; and

FIGURE 6 is a front isometric view with the portable handle extended.

The rectangular window is diagonally lined to indicate transparency and the legible matter shown in broken lines is shown for illustrative purposes only.

I claim:

The ornamental design for the portable digital meter, as shown and described.
